Primary Examiner — Robert M Spear*Assistant Examiner* — Ryan Harvey*(74) Attorney, Agent, or Firm* — McDermott Will & Emery LLP**CLAIM**

We claim the ornamental design for a hand driven ride-on vehicle, as shown and described.

DESCRIPTION

FIG. 1 is a top, front and right side perspective view of a hand driven ride-on vehicle according to the new design.

FIG. 2 is a bottom, rear and left side perspective view of the hand driven ride-on vehicle shown in FIG. 1.

FIG. 3 is a front elevation of the hand driven ride-on vehicle shown in FIG. 1.

FIG. 4 is a left side elevation of the hand driven ride-on vehicle shown in FIG. 1.

FIG. 5 is a right side elevation of the hand driven ride-on vehicle shown in FIG. 1.

FIG. 6 is a rear elevation of the hand driven ride-on vehicle shown in FIG. 1.

FIG. 7 is a top plan view of the hand driven ride-on vehicle shown in FIG. 1; and,

FIG. 8 is a bottom plan view of the hand driven ride-on vehicle shown in FIG. 1.

Features shown in broken lines in the drawings are not part of the claim.
